(57) CLAIM

The ornamental design for a protector for a backhoe, as shown and described.

DESCRIPTION

FIG. 1 is a rear view of a protector for a backhoe showing our claimed design;

FIG. 2 is a right side view thereof;

FIG. 3 is a left side view thereof;

FIG. 4 is a left rear perspective view thereof; and,

FIG. 5 is a right rear perspective view thereof. However, the part of the photograph shown in a coarse dot pattern and outlined in dashed lines illustrates a portion of the backhoe that forms no part of the claimed design.
